(57) **CLAIM**

The ornamental design for the cookware handle, as shown and described.

DESCRIPTION

FIG. 1 is a perspective front and left side view of the cookware handle showing the new design;

FIG. 2 is a front elevation view of the cookware handle of FIG. 1;

FIG. 3 is a rear elevation view of the cookware handle of FIG. 1;

FIG. 4 is a left side elevation view of the cookware handle of FIG. 1, the right side view being a mirror image thereof; FIG. 5 is a top plan view of the cookware handle of FIG. 1; FIG. 6 is a bottom plan view of the cookware handle of FIG. 1;

FIG. 7 is a perspective view of the cookware handle in its environment;

FIG. 8 is a perspective front and left side view of a second embodiment of the cookware handle;

FIG. 9 is a front elevation view of a second embodiment of the cookware handle;

FIG. 10 is a rear elevation view of a second embodiment of the cookware handle;

FIG. 11 is a left side elevation view of the cookware handle of second embodiment of the cookware handle, the right side view being a mirror image thereof;

FIG. 12 is a top plan view of a second embodiment of the cookware handle;

FIG. 13 is a bottom plan view of a second embodiment of the cookware handle; and,

FIG. 14 is a perspective view of a third embodiment of the cookware handle in its environment.

The ornamental design which is claimed is shown in solid lines in the drawings. The broken lines in the drawings are for illustrative purposes only and form no part of the claimed design.
